SHEET POSITIONING ATTACHMENT

Richard E. Wilburn, Leavenworth, Kans.

Application April 19, 1948, Serial No. 21,944

8 Claims. (Cl. 271—26)

1

My invention relates to sheet positioning attachments for automatic platen printing presses, and more particularly to such an attachment for use with the Kluge automatic platen press of the type shown in the patent to Kluge No. 2,318,165, patented May 4, 1943.

In a press of the above referred to type suction fingers are provided for feeding the paper sheets from a magazine to the platen. Paper that is cut the wrong way of the grain, paper that is green and not properly cured, or that is curled or otherwise affected by temperature or other atmospheric conditions, and light weight paper, such as manifold, tissue and onion skin papers, are difficult to feed properly with a press of this type. This is especially true of light weight papers, which, when fed at other than a very slow speed, do not properly settle on the platen so as to lie flat thereagainst, due to the fact that air is trapped between the sheet and the platen after the sheet is placed on the platen. Inasmuch as the sheet is not properly settled on the platen when the impression is made this causes a "slur" to the printed matter and irregular registry. Also frequently a sheet, due to this trapping of air, eludes the grippers and is pulled into the rollers of the press, resulting in loss of time and waste of materials.

By the use of my attachment to a press of this character forming the subject matter of this invention these traps are entirely overcome because the sheet is placed flat on the platen, thus eliminating the trapping of air so that regardless of the press speed perfect registry is assured even without the use of a standard side register gauge.

Not only has my invention the advantage that more perfect work results and loss of time and materials is avoided by the use thereof, but in addition to that the production is increased from fifty to one hundred percent because of the increased rate of feeding that is possible, particularly with light weight papers, and because there are no interruptions in the operation of the press due to improperly fed paper becoming entangled with other parts of the press.

My attachment is used in conjunction with the suction feeding means for the paper and is carried by the moving parts of this feeding mechanism, being adjustably mounted thereon for adjustment for different size sheets and being itself adjustable in accordance with the size of sheet that is to be fed.

More specifically my invention comprises a pair of paper engaging fingers that are adjustable in length and the angular position of which rela-

2

tive to the mounting for the suction fingers is adjustable so that said paper engaging fingers will engage the paper in a proper manner when placed on the platen so as to smooth out the paper and lay the same flatly on the platen and prevent any entrapment of air between the paper and the face of the platen.

Other objects and advantages of my invention will appear as the description of the drawings proceeds. I desire to have it understood, however, that I do not intend to limit myself to the particular details shown or described, except as defined in the claims.

In the drawings:

15 Fig. 1 is a view in side elevation of a portion of an automatic platen press of the character to which my invention is applied, showing my feeding attachment applied thereto.

20 Fig. 2 is a fragmentary view in side elevation of such a press, showing my feeding attachment in position to engage the sheet with the platen.

Fig. 3 is a view partly in elevation and partly in section, on a slightly larger scale than Figs. 1 and 2, of my attachment and a portion of the 25 feeding mechanism of the press, with the parts in an intermediate position between the magazine and the platen.

Fig. 4 is a fragmentary plan view of the parts shown in Fig. 3.

30 Fig. 5 is a plan view on a smaller scale, of the platen, showing a sheet placed in position thereon by the feeding means to which my attachment has been applied.

Fig. 6 is a section taken on the line 6—6 of 35 Fig. 3, and

Fig. 7 is a section taken on the line 7—7 of Fig. 3.

Referring in detail to the drawings, in Figs. 1 and 2 portions of a printing press 10 are shown, 40 which has a platen 11, the platen being shown in the position to make the impression in Fig. 1, and in the position for receiving the paper in Fig. 2. A press of the character to which my invention is applied is provided with a feeding

45 mechanism that has a movable arm 12 that is moved from the position shown in Fig. 1 to that shown in Fig. 2 by means of rotatable member 13, with which the arm 12 is pivotally connected at 14. Said arm 12 has a cross bar 15 thereon that is usually square in cross section.

A plurality of suction fingers 16 having the suction nozzles 17 thereon is mounted on the bar 15. The suction nozzles are connected with a suction creating means through the flexible tubular members 18, which are mounted on the arm

12 so as to move with said arm 12 and the cross bar 15. The details of construction of this suction feeding apparatus are not part of my invention and only sufficient thereof is described to properly illustrate my invention. The sheet feeding mechanism further comprises a magazine that has an inclined bottom wall 19 and a follower 20, which is advanced by suitable mechanism step by step to move upwardly along the inclined bottom 19 as the press operates. A holding arm 21 is also provided for holding the top-most sheet of the stack when the suction feeding fingers are moved away from the top of the stack, suitable mechanism being provided for moving this arm 21 in timed relation to the feeding mechanism.

My attachment for properly placing the sheets on the platen is mounted on the bar 15 and comprises a main body portion or head 22, there being two of said members 22 provided, as my attachments are used in pairs on a press, being located on the bar 15 between the suction fingers 16 in the manner illustrated in Fig. 5. The body portion 22 has an opening that is square in cross section and is longitudinally slidably mounted on the square bar 15. The members 22 are provided with resilient means for holding the same in adjusted position on the bar 15, the members 22 being movable toward and away from each other on the bar 15 and being spaced apart a distance dependent upon the length of the sheet of paper that is being fed transversely of the platen. Said resilient means comprises a spring finger that has an upstanding portion 23 that is secured to the side face of the body portion 22 by means of a screw 24 and a spring finger 25 that has a downwardly bent or deflected end portion 26 that engages the flat upper face of the bar 15 in the position shown in Fig. 3.

Each of said body portions has a transverse slot 27, which provides a flange or upstanding ear 28 on said body portion. Said ear or flange and the upper portion 29 of said body portion 22 have aligning openings 30 therein that are unthreaded and which receive the threaded shank portion 31 of an arm that has a portion 32 extending at an oblique angle to the threaded portion 31. A knurled collar 33 is provided, which has screw-threaded engagement with the screw-threaded portion 31 of the arm to thus make the arm adjustable in the openings 30. A lock nut 34 is provided for locking the arm in adjusted position.

The extremity of the obliquely extending portion 32 of the arm has a bracket 35 pivotally mounted thereon by means of a pivot pin 36 that extends through an opening in the angular arm 32 and through aligning openings in the ears 37 on said bracket. The bracket has a pair of recesses 38 in the opposite end thereof that have curved walls to define a pair of curved flanges 39, in which a channeled bar 40 is mounted. The channeled bar 40 has a pair of hook flanges 41 extending along the longitudinal margins thereof and is an extension of a bracket 42, which is pivotally mounted on a depending ear 43 at the lower end of the body portion 22, the member 42 being bifurcated at the end 44 thereof and a pivot pin 45 extending through the bifurcations of said bracket 42 and the ear 43. The guide bar 40 is thus adapted to pivot about the pivot member 45 as an axis as the bracket 35 is adjusted by means of adjustment of the position of the obliquely extending arm 32 by turning the adjusting member 33.

Slidably mounted in the guide bar 40 is a flexible metal finger 46, said finger 46 fitting closely between the hook flanges 41 so that it will be held in adjusted position by the frictional engagement between the walls of the guide member and the flexible metal finger 46. Said flexible metal finger is thin and wide and flat, but has a slightly angularly deflected end portion 47, which, preferably, has rounded corners 48 as shown in Fig. 4. There are two of the guide bars 40 and two of the flexible fingers 46 provided and these are, preferably, so arranged that the out-turned ends 47 thereof have their extremities 49 terminating slightly beyond the rear edge 50 of the sheet 51 that is being fed to the platen, both while moving toward the platen and upon engagement of the sheet 51 with the platen, the suction nozzle 17 engaging the sheet 51 near the forward edge 52 of said sheet. The sheets are customarily fed 10 with their length extending crosswise of the platen so that the edges 50 and 52 are side edges of the sheet.

In operation the guide bars 40 and the wide flexible metal fingers 46 are in a position substantially parallel to the top face of the stack of sheets 51 in the magazine when the parts are in the position shown in Fig. 1. The movement of the arm 12 is such that the bar 15 moves substantially perpendicularly to the upper or forward face of the stack in moving the suction fingers and parts carried by the bar 15 away from the magazine until a position is reached where the inclined bottom wall 19 of the magazine is fully cleared, whereupon the parts swing in a long sweeping arc toward the platen. It will be noted that my improved feeding attachment is so located that it will not interfere in any manner with the feeding motions of the suction nozzles or fingers, or in any manner with the holding finger 21 or any of the parts of the magazine in its movements with the cross bar 15. In moving the sheet from the position shown in Fig. 1 through the position shown in Fig. 3 to the position shown in Figs. 2 and 5 the suction nozzle, which is gripping the sheet near the forward or advancing edge 52 thereof, pulls the top sheet from the stack and moves it in a sweeping motion toward the platen. At the same time the flexible finger 46 of my improved feeding attachment engages the sheet 51 near the trailing edge 50 thereof and said sheet is held substantially in a straight or distended position as it is swept down toward the platen. Upon engagement with the platen, the fingers 46 smooth out the sheet and lay it flatly on the platen so as to prevent any substantial amount of air from being trapped under the sheet 51 and thus between the sheet 51 and the platen 11. This assures the proper location of the sheet on the platen in engagement with the grippers usually provided and assures the settling of the sheet flatly on the platen before the platen begins its movement into impression making position, the entire sheet feeding mechanism beginning its return movement before the movement of the platen toward the impression making position is begun and thus the arm 12 and all parts carried thereby are out of the way, being in the process of moving back to the position shown in Fig. 1 before the platen 11 has moved to the position shown in Fig. 1. After the impression has been made and the platen is returned substantially to the position shown in Fig. 2, suitable means that are customarily provided remove the printed sheet from the platen and deposit it on a stack of printed sheets 53.

whereupon the feeding operations above described are repeated.

In order to have the wide yielding metal fingers engage the sheet 51 at the proper position, it is necessary that the effective length of the fingers be adjusted by sliding the fingers in and out of the guide bars 40, dependent upon the width of sheet that is fed. Also the angularity of the guide bar 40 must be adjusted to get the proper bearing of the fingers 46 on the sheet, this being accomplished by means of the adjusting member 33. Furthermore the fingers 46 must be adjusted to obtain the desired spacing thereof lengthwise of the sheet or crosswise of the platen, this being done by adjusting the body portions 22 lengthwise of the bar 15. It will be noted that due to the curved recesses 38 provided in the bracket 35 there will be a central bearing 54 for the guide bar 40 in the bracket 35, said guide bar engaging the bracket at the point 54 and the ends of the hook flanges 39, thus providing for the ready adjustment of the member 40 relative to the bracket 35.

What I claim is:

1. In a sheet feeding mechanism for platen presses, the combination with transversely spaced movable suction nozzles for transferring sheets one at a time from a magazine to a platen, of a pair of transversely spaced fingers on said feeding mechanism mounted to move in unison with said nozzles throughout the movement of said nozzles and having sheet engaging portions longitudinally spaced from said nozzles, means for adjusting the position of said fingers relative to said nozzles, and means for maintaining said fingers in fixed position relative to said nozzles for any adjusted position thereof.

2. In a sheet feeding mechanism for platen presses, the combination with transversely spaced movable suction nozzles for transferring sheets one at a time from a magazine to a platen, of a pair of transversely spaced fingers on said feeding mechanism mounted in a fixed adjusted position to move in unison with said nozzles throughout the movement of said nozzles and having sheet engaging portions longitudinally spaced from said nozzles, the transverse spacing of said fingers and the length thereof being adjustable.

3. In a sheet feeding mechanism for platen presses, the combination with transversely spaced movable suction nozzles for transferring sheets one at a time from a magazine to a platen, of a pair of transversely spaced fingers on said feeding mechanism mounted to move with said nozzles in unison and having sheet engaging portions longitudinally spaced from said nozzles, means for mounting said fingers in fixed position relative to said nozzles and means for adjusting said mounting to adjust said position, comprising means for adjusting the angularity of said fingers relative to said mounting and means for adjusting the length of said fingers.

4. In a sheet feeding mechanism for platen presses, the combination with movable suction nozzles for transferring sheets one at a time from a magazine to a platen mounted on a transverse bar, of a pair of members mounted on said bar for adjustment longitudinally thereof, and fingers mounted for angular adjustment relative

to said members, said fingers having yieldable sheet engaging portions.

5. In a sheet feeding mechanism for platen presses, the combination with movable suction nozzles for transferring sheets one at a time from a magazine to a platen mounted on a transverse bar, of a pair of members mounted on said bar for adjustment longitudinally thereof, and fingers mounted for angular adjustment relative to said members, said fingers each comprising a pair of telescopically related members whereby the length of said fingers is adjustable.

15 6. In a sheet feeding mechanism for platen presses, the combination with movable suction nozzles for transferring sheets one at a time from a magazine to a platen mounted on a transverse bar, of a pair of members mounted on said bar for adjustment longitudinally thereof, and fingers mounted for angular adjustment relative to said members, said fingers each comprising a pair of telescopically related members whereby the length of said fingers is adjustable, one of said telescopically related members being yieldable and engaging the sheet being transferred.

25 7. In a sheet feeding mechanism for platen presses, the combination with movable suction nozzles for transferring sheets one at a time from a magazine to a platen mounted on a transverse bar, of a pair of members mounted on said bar for adjustment longitudinally thereof, and a finger pivotally mounted on each of said members, a finger supporting bracket, and means for adjustably mounting said bracket on said member, said bracket engaging said finger in spaced relation to its pivotal mounting, said fingers comprising flexible members and members mounting said flexible members for longitudinal adjustment relative thereto whereby the length of said fingers is adjustable.

30 40 8. In a sheet feeding mechanism for platen presses, the combination with movable suction nozzles for transferring sheets one at a time from a magazine to a platen mounted on a transverse bar, of a pair of members mounted on said bar for adjustment longitudinally thereof, and a finger pivotally mounted on each of said members, a finger supporting bracket, and means for adjustably mounting said bracket on said member, said bracket engaging said finger in spaced relation to its pivotal mounting, said fingers comprising flexible members and members mounting said flexible members for longitudinal adjustment relative thereto whereby the length of said fingers is adjustable, said flexible members being wide and flat and having angularly extending end portions.
